UNITED STATES PATENT OFFICE.

MORRIS S. WRIGHT, OF WORCESTER, MASSACHUSETTS.

FOLDING PEDAL FOR PIANOLAS.

SPECIFICATION forming part of Letters Patent No. 766,312, dated August 2, 1904.

Application filed July 8, 1902. Serial No. 114,726. (No model.)

To all whom it may concern:

Be it known that I, MORRIS S. WRIGHT, a citizen of the United States, residing at Worcester, in the county of Worcester and Commonwealth of Massachusetts, have invented a new and useful Improvement in Folding Pedals for Pianolas, of which the following is a specification, accompanied by drawings, forming a part of the same, in which—

10 Figure 1 is a view in section through the frame of the pianola, showing my improved pedal in elevation, in full lines in operative position, and in dotted lines to indicate its position when folded or collapsed, dotted lines also indicating the expanded position of the feeder. Fig. 2 is a view in front elevation. Fig. 3 is a perspective view of one of the pedals looking from beneath.

15 Similar reference-figures refer to similar parts in the different views.

The object of this invention is to provide means for folding and inclosing the pedals into compact space within the frame of the instrument without the necessity of having a 20 large opening in the outer face of the pianola for that purpose, provision being made by my invention for the withdrawal of the pedals approximately in a straight inward direction without any appreciable upward movement, which in other pedals capable of being collapsed into the frame is accomplished by a vertical motion, as well as horizontal, necessitating a large opening in the front of the frame therefor, which opening is unsightly 25 and objectionable and in my invention rendered unnecessary.

With this object in view my invention consists in jointed mechanism so arranged and devised that the normal position of the pedals is practically preserved whether in their outward or collapsed position, and I contemplate such an arrangement of parts that this collapse may be readily effected by the operator simply pushing the pedal mechanism in 40 with the toe, after which it may be drawn outward when desired in the same manner, and to facilitate this action of course regard is had to the weight and proportions and balancing of different parts of the mechanism, so 45 as to make the movement of the folding ped-

als in and out as easy as possible without of any wise detracting from the general aim in the invention, which has been stated.

Referring to the accompanying drawings, 50 1 indicates the outer case, a portion only of 55 which is shown, mounted after the usual fashion on casters for convenience.

2 denotes the bellows-frame, which of course is stationary, and 3 represents the feeder hinged at its upper end thereto in the usual 60 manner, although not shown, and adapted to swing through an area indicated by the dotted lines at the right-hand end of Fig. 1. A bracket 4 is attached to this feeder, its lower end reaching forwardly, as indicated, and provided at its end with a bearing 5. The pedal-frame is made in two parts 6 and 7, the part 6 being screwed, bolted, or otherwise secured to the bottom of the case a suitable distance 65 from its outer edge, as indicated in Fig. 1, 70 and the other part, 7, is movable and is adapted to slide in and out and when in its outer position to rest upon a foot 8, as indicated in Figs. 1 and 2. To this movable section 7 of the frame the pedal 9 is hinged, as indicated, 75 upon the rod 10, supported in the upturned ears 11 11. The upper end of the pedal is supported at each side by means of connecting-rods 12 12, pivoted at their upper ends, as at 13, to the ears 14 14 and at their lower 80 ends in the bearings 5 5 of the brackets 4 4. So much of the mechanism is sufficient for the usual operation of the pedal. Co-operating with it, however, is a pair of toggle-joints 15 15, one on either side. These toggle-joints 85 are secured at their outer ends to section 7 of the frame and pivotally connected at their inner ends, as at 16, to the stationary frame-section 6. These toggle-joints are so constructed and arranged that they form a lock 90 by gravity, which retains the outer movable section 7 of the frame in the normal position. (Indicated in Fig. 1.) When the pedals are folded, the joint of the toggle readily breaks, and the joint folds into the collapsed position, 95 (indicated in the dotted lines in Fig. 1,) the section 7 taking a quarter-turn, as indicated in that figure, owing to the fact that the toggle-joint is rigidly secured to it and not pivoted. The pedal itself assumes the position indicated 100.

22
5 by the diagonal dotted lines when pushed inwardly, and the connecting-rods 12 12 assume an approximately vertical position, as therein indicated, and to insure this collapse a rest 15^a is adapted to limit the downward movement of the toggle-joint to prevent dropping into alinement or beneath a dead-center, as in that position it could not readily be collapsed.

As alluded to in the statement of the purposes of the invention, the various parts may be so weighted and proportioned as to balance and counterbalance one another as nearly as possible, and in this way the control of the position of the pedals is made perfectly easy. 15 It will likewise be understood that the construction is such that there is no tendency of the pedals to push inward when in operation, as it requires an application of pressure upon the frame-section 7 direct and with an inward 20 and slightly-upward motion to fold the pedals.

Slight alterations in the form and dimension, as well as arrangement, of the several parts described may of course be made without departing from the spirit and scope of my 25 invention, and hence I do not wish to be limited to the precise construction set forth.

What I claim as my invention, and desire to secure by Letters Patent, is—

1. The combination with a case, a bellows-frame and feeder supported therein, of a folding 30 frame and feeder pivotally connected at one end with said feeder, and a pair of toggle-joints 15, 15 pivotally connecting the opposite end of said pedal with said case, said toggle-joints being 35 pivoted together, substantially as described.

2. A folding pedal comprising two frame-sections one stationary and the other movable, the pedal hinged to the latter, and the two connected together by toggle-joints whereby 40 an inward application of pressure upon the pedal will fold the joint and permit the movable section with the attached pedal to move inwardly.

3. The combination with a bellows-feeder, 45 a pedal and connecting-rods extending from

the pedal to the bellows, of a collapsible frame comprising a stationary and movable section, the pedal hinged to the latter and a toggle-joint rigidly secured to the movable section and pivoted to the stationary section, and constructed and adapted to fold in response to an inward movement of the movable section of the frame.

4. The combination with a bellows-feeder, a bracket secured thereto, a hinged pedal and 55 a connecting-rod pivoted to the pedal and bracket, of a folding or collapsible frame comprising a stationary and movable section and toggle-joints connecting them together, the toggle-joints pivoted to the stationary 60 section and secured rigidly to the movable section, and means for preventing the toggle-joints from reaching a dead-center.

5. The combination with the case of a 65 pianola, a bellows frame and feeder therein and a hinged pedal operative, connected with said feeder, of a folding, collapsible frame consisting of two sections and toggle-joints connecting these sections, one section fixed in the case of the pianola, and the other section 70 movable and having the pedals hinged thereto, the toggle-joints pivoted to the fixed section and secured to the movable section whereby to permit the pedals to be folded into the case of the pianola.

6. A folding pedal normally held in an inclined position, a movable frame pivotally connected with the lower end of said pedal, toggle-joint links pivotally connecting said 80 movable frame with a fixed point, a bellows frame and feeder, upwardly-projecting brackets attached to said pedal at its upper end and links pivotally connecting said brackets with said feeder, substantially as described.

Dated this 1st day of July, 1902.

MORRIS S. WRIGHT.
